IRA VAN PELET AND JOHN S. VAN PELET, OF PETERSBURG, VIRGINIA.

Letters Patent No. 77,132, dated April 21, 1868.

IMPROVEMENT IN CARRIAGE-COUPING.

The Schedule referred to in these Letters Patent and making part of the same.

TO ALL WHOM IT MAY CONCERN:

Be it known that we, IRA VAN PELET and JOHN S. VAN PELET, of Petersburg, in the county of Dinwiddie, and State of Virginia, have invented a new and improved Carriage-Coupling; and we do hereby declare the following to be a full, clear, and exact description of the same, sufficient to enable those skilled in the art to which our invention appertains to make use of it, reference being had to the accompanying drawings, forming part of this specification, in which—

The drawing is a longitudinal vertical section through the centre of a carriage containing our improvement.

In this invention the use of coupling-bars is dispensed with, and a carriage is made without them, which is simpler in construction, stronger, and works better than the carriages in which such bars are employed.

In the drawing, A represents the body of our improved carriage; B, one of the forward wheels; C, the forward axle; D, the tongue; E, the swingle-tree; F, the fifth-wheel or circle; and G, the bolster. There is nothing peculiar in the construction of these parts, except as will be hereafter described.

H is the king-bolt, extending through both the bolster and axle-tree. The bolster is slotted at e, as shown in the drawing, the king-bolt passing vertically through the centre of the slot.

A chain, I, extends from the centre of the swingle-tree to the bolster, and is attached to the king-bolt within the slot e. From each end of the swingle-tree, a chain, J, extends to the axle-tree, and is fastened to it by means of a staple or other suitable device. The three chains, I, J J, being of equal length, the swingle-tree would not turn on its pivot in turning the wagon were not some provision made to enable it to do so. We therefore attach the swingle-tree to a sliding pivot, i, moving back and forth in a slot, s, in the carriage-tongue. As thus constructed, when the draught is directly forward, the pivot and swingle-tree will work at the forward end of the slot, as shown in the drawing; but when the carriage is turning they will slide back towards the rear end of the slot, and so slacken the middle chain I and the chain on the side towards which the carriage is turning, that the swingle-tree can swing on its axis sufficiently to accommodate itself to the movement of the carriage.

In operating thus, it is evident that it relieves the king-bolt of all undue pressure when turning the carriage, bringing the strain upon the tongue and outside chains J J alone.

One of the chains, I, being attached to the bolster above the circle F, and the other two, J J, below it to the axle, the strain is brought at all times equally upon both axle and bolster, relieving the king-bolt, and making the coupling peculiarly strong and firm. The carriage can be made at less expense in this way than in the old way, and while it works as easily, is stronger than when constructed with coupling-bars connecting the bolster and rear axle. The latter, in our carriages, is attached to the wagon-body, and not connected in any way with the forward axle or bolster.

Having thus described our invention, what we claim as new, and desire to secure by Letters Patent, is—

The combination of the sliding pivoted swingle-tree E with the chains I, J J, axle C, and bolster G, substantially as and for the purposes specified.
